FIG. 1.

FIG. 2.

FIG. 3.

Frederick Wilson
Inventor

By Geo. P. Kimmel.

Attorney

UNITED STATES PATENT OFFICE.

FREDERICK WILSON, OF ROOSEVELT, NEW YORK.

WEATHER-STRIP.

1,361,657.

Specification of Letters Patent.

Patented Dec. 7, 1920.

Application filed February 28, 1917. Serial No. 151,469.

To all whom it may concern:

Be it known that I, FREDERICK WILSON, a citizen of the United States, and resident of Roosevelt, in the county of Nassau and State 5 of New York, have invented certain new and useful Improvements in Weather-Strips, of which the following is a specification.

The present invention relates to new and useful improvements in weather strips, and 10 has particular reference to a wooden strip adapted to be associated with window sashes.

My invention comprises a plurality of co-operating members adapted when joined to form the desired air-tight joint. The co- 15 operating members have means associated therewith to overcome any warping of the members which may be caused by damp weather.

Other improvements and novel details in 20 the construction and arrangement of the various parts of the apparatus will be brought out more in detail in the description to follow, which, for a clear understanding of the invention, should be considered in connection with the accompanying drawing, 25 forming a part hereof, and wherein is disclosed, for the purpose of illustration, convenient and satisfactory embodiments of the invention. It is to be noted, in this connection, that minor changes in the construction and arrangement of the parts may be made 30 without departing from the spirit of the invention or the principle of operation of the various parts.

35 In the drawing:

Figure 1 is a vertical sectional view showing my invention as applied to the lower sash of a window having a co-operating member formed on the sill thereof;

40 Fig. 2 is a vertical sectional view of the meeting rails of the upper and lower sash with my improved strip applied, and

Fig. 3 is a longitudinal sectional view of a window frame showing my invention as applied to the sides of the window sash and a co-operating member used in place of the common form of outer beading.

Similar reference characters indicate corresponding parts throughout the several 50 views in the drawing.

Referring particularly to Fig. 1 of the drawing, "1" designates a standard form of window sill and "2" the lower sash having a weather stripping designated W in its en-

tirety, the weather stripping W comprising a 55 pair of members 4 and 5 respectively, the member 4 being carried by the sash 2, while the member 5 is carried by the sill 1. Each member includes a body portion 3 having a stepped extension 6 presenting intermediate 60 and outer surfaces *a* and *b* respectively, the extension 6 of both members being designed to overlap each other so that the intermediate surfaces *a* will be spaced apart relative to each other, while the outer surfaces of said 65 extensions at all times contact with each other in the disposition of the weather stripping W in use with the window. The extensions 6 are sufficiently narrowed in thickness, so as to maintain the proper spacing apart of 70 the intermediate surfaces *a* of the members 4 and 5 when assembled and secured in place in a window.

The contacting of the outer surfaces *b* of the members 4 and 5 obviously avoids warping 75 of these members and particularly at their portions throughout the spaced intermediate surfaces *a*.

The preferred form of my invention is set forth in Fig. 2 wherein is presented the meeting rails 7 and 8 having the co-operating weather strips of my invention formed adjacent the meeting edges thereof. The extension 4' is shown extending over the extension 6' for an obvious purpose. The spacing 80 9 provides means for overcoming the warping of the wood as above set forth.

In Fig. 3 I have shown one of my co-operating members 4' used in connection with the outer beading as employed on all standard 90 window frames. The weather stripping having the extension 6 is attached along the outer edge of the side rail of the window and is slidably mounted thereon thus presenting the desired air-tight joint at practically 95 the same cost as the forms now used.

While I have herein illustrated and described with a considerable degree of particularly constructional details of the weather strip embodying my invention, it is 100 to be understood that the invention is not limited to the particular form and arrangement of the several parts which may be modified within a wide range without departing from the essence of the invention, 105 the construction shown and the description based thereon being intended to be taken in an illustrative rather than a limiting sense.

I claim:

The combination with relatively movable parts, of weather stripping members, each secured to one of said parts, said members having body portions provided with stepped extensions overlapping one another and presenting adjacent intermediate and outer sur-

faces at right angles to each other, the intermediate surfaces being spaced apart, while the outer surfaces of said extensions at all 10 times contact with each other.

In testimony whereof, I affix my signature hereto.

FREDERICK WILSON.
